(57) **CLAIM**

The ornamental design for a showerhead, as shown and described.

DESCRIPTION

FIG. 1 is a perspective view of a showerhead showing my new design;

FIG. 2 is a front elevational view of the showerhead showing my new design; and,

FIG. 3 is a right side elevational view of the showerhead showing my new design, with a left side elevational view, a top view and a bottom view being mirror images thereof. The broken line showing is included for the purpose of illustrating and forms no part of the claimed design.

1 Claim, 3 Drawing Sheets

FIG. 1

FIG. 2

FIG. 3
